UNITED STATES PATENT OFFICE.

CLARK J. DUNCAN, OF WINDBER, PENNSYLVANIA.

BURIAL-CASE.

SPECIFICATION forming part of Letters Patent No. 729,921, dated June 2, 1903.

Application filed August 28, 1902. Serial No. 121,267. (No model.)

To all whom it may concern:

Be it known that I, CLARK J. DUNCAN, a citizen of the United States of America, residing at Windber, in the county of Somerset and State of Pennsylvania, have invented 5 certain new and useful Improvements in Burial-Cases, of which the following is a specification, reference being had therein to the accompanying drawings.

This invention relates to certain new and useful improvements in burial-cases, and has for its object to construct a case which when sealed will be impervious to dampness, and in addition the invention has for its object 15 to provide means for absorbing any moisture that may be within the case in one form or another at the time of sealing.

To this end the invention resides in the novel construction and arrangement, which 20 embody substantially a case composed of artificial stone, vitrified material, porcelain, or any such substance which will be impervious to moisture. The case near its upper edge is provided with a ledge and also with a 25 groove. The ledge is to receive the lid, and a gasket is placed on the ledge, between the latter and the lid, so as to form a tight joint therewith. The lid is also provided with a 30 groove running around the same, and in this groove and in that of the case is placed a cement or like substance, forming a seal and securely fastening the lid to the case, also assisting in the rendering of a moisture-proof 35 joint between the case and the lid. The case is or may be provided on its inner face with vertically or otherwise disposed grooves, and these grooves are adapted to receive a filling of moisture-absorbing material. The lid of the case is provided with openings to receive 40 lowering straps or cords, and the case is provided with handles for ease in handling the same, all of which construction will be hereinafter more specifically described and then particularly pointed out in the claim.

In describing the invention in detail reference will be had to the accompanying drawings, forming a part of this specification and wherein like numerals of reference will be employed to designate like parts throughout 45 the different views of the drawings, in which—

Figure 1 is a side elevation of my improved

burial-case. Fig. 2 is a top plan view thereof with a portion of the lid broken away, so as to show the interior construction of the case. Fig. 3 is a transverse vertical sectional view of the case. Fig. 4 is a detail perspective view of one of the strips of absorbent material placed in the interior of the case.

To put my invention into practice, I provide a case 1, which, as stated, is composed 60 of a hard substance, such as vitrified clay or artificial stone, or may be made of porcelain or the like and material of this nature which is a repellent to moisture and which is cheap enough to manufacture. This case 1 is preferably molded and is provided with exterior strengthening-ribs 2 and has one or more handles 3 on each side for ease in manipulation or handling of the case. At its upper edge this case is formed with an overlying rim 4, 70 which is recessed in its upper face to form a shoulder or ledge 5, in which is mounted, partially countersunk therein, a gasket 6, which may be of rubber or other compressible material. The vertical wall of the shoulder 5 is formed with a groove 7, the two horizontal walls of which are parallel and the rear wall of which is at an incline, making the groove substantially dovetail in its form. A groove of like construction to this is formed 75 in the lid 8, the groove 7' in the lid and the groove 7 in the rim of the case being opposite each other. The lid 7 is constructed with a flange 9, which rests upon the shoulder or ledge 5 of the case, fitting the same neatly 80 and provided in its inner face with a groove or recess which receives the gasket 6. The lid is also constructed with a downwardly-extending flange 10, which fits against the inner face of the case, as seen in Fig. 3. 90

I preferably construct the case 1 with grooves 11 on its inner face. In the present illustration these grooves are shown dovetail in form and are arranged vertically of the case, though the grooves may be arranged longitudinally of the case, if desired, or both vertically and horizontally. They are adapted to receive the filling or packing strips of absorbent material 14, composed of okum or any suitable absorbent material. The dovetail nature of the grooves serves to retain 95 this absorbent material in position, and the

employment of the material serves to absorb any moisture which may be in the case when the latter is sealed.

The lid is sealed to the case after being placed thereon by a suitable composition, as shown at 15, such as cement, which when it hardens assists in rendering the joint air-tight and practically renders the lid immovable from the case. This cement sealing composition when in its plastic state fills in the grooves 7 and 7', as seen in Fig. 3, so that the lid is securely sealed. The lid is also constructed with strengthening-ribs, which may pass in different directions across the same and through one or more of which suitable openings 16 are provided to receive lowering straps or cords to facilitate lowering of the case into a grave or vault.

In the construction of the case it will be

observed that various slight changes may be made in the details of construction without departing from the general spirit of my invention.

Having fully described my invention, what I claim as new, and desire to secure by Letters Patent, is—

The combination with the burial-case having the inner faces of its side walls formed with a plurality of dovetail grooves, of strips of absorbent material of similar contour in cross-section to said grooves arranged therein, and a cover for said case.

In testimony whereof I affix my signature in the presence of two witnesses.

CLARK J. DUNCAN.
